ROTARY MOTION TRANSLATING DEVICE

Arthur B. Poole, Bristol, Conn., assignor to The
E. Ingraham Company, Bristol, Conn., a cor-
poration of Connecticut

Application June 29, 1939, Serial No. 281,807

10 Claims. (Cl. 74—112)

The present invention relates to improvements in rotary motion translating devices of the character wherein a continuous rotary motion may be translated or transposed into an intermittent or step-by-step rotary motion. The translating devices of the present invention are primarily designed for effecting the periodic actuation of an electric switch device though also available for many other uses.

10 One of the objects of the present invention is to provide a superior device of the character referred to, by means of which a relatively-slow substantially-continuous rotary motion of a driving-member may be converted or translated into a relatively-rapid step-by-step rotary motion without deterioration of the parts despite long periods of service.

Another object of the present invention is to provide a superior rotary motion translating device which will accomplish the desired translating of a continuous or substantially-continuous rotary motion into periodic rapid 360° motion of one continuous and rapid sweep without requiring an undue number of parts.

25 A further object of the present invention is to provide a device of the character referred to, which may be produced at a low cost of manufacture and which will withstand long periods of severe usage without occasioning the breakdown of the parts.

30 With the above and other objects in view, as will appear to those skilled in the art from the present disclosure, this invention includes all features in the said disclosure which are novel over the prior art and which are not claimed in any separate application.

35 In the accompanying drawings, in which certain modes of carrying out the present invention are shown for illustrative purposes:

40 Fig. 1 is a view in front elevation of one form which a rotary motion translating device may assume in accordance with the present invention and showing a portion of the front-plate broken away and some of the remaining parts in partial section, for purposes of clarity of illustration;

45 Fig. 2 is a top or plan view thereof;

Fig. 3 is a sectional view taken on the line 3—3 of Fig. 2;

50 Fig. 4 is a view corresponding to Fig. 3 but showing the parts in the positions which they assume an instant prior to the release of the stop-arm;

55 Fig. 5 is a corresponding view but showing the parts in the positions which they assume an instant following the release of the stop-arm;

Fig. 6 is a broken transverse sectional view taken on the line 6—6 of Fig. 1;

Fig. 7 is a perspective view of the unit comprising the driven-pinion, stop-arm, spring-barrel and shaft, detached;

Fig. 8 is a perspective view of the unit comprising, in the main, the driving-wheel and the latch-releasing member carried thereby;

Fig. 9 is a perspective view of the latch-releasing member, detached; and

Fig. 10 is a perspective view of the latching-member, detached.

For purposes of making clear the character of the present invention, one form thereof has been chosen for illustration in the accompanying drawings and for detailed description. The particular rotary motion translating device shown, includes a front-plate 20 and a back-plate 21, both of circular outline and both rigidly coupled together in parallel spaced-relationship by means of a plurality of pillars 22. Mounted against the rear face of the back-plate 21, is a synchronous electric motor-structure designated by the reference character 23 and which may be of any appropriate form requiring no detailed description herein, other than to point out that, as shown, the said motor-structure is provided with a power-output shaft 24 carrying a driving-pinion 25. The said driving-pinion is driven by the synchronous electric motor-structure 23 with an accurately-timed rotational movement, and meshes into and drives a driving gear-wheel 26 which has staked to it a hub 27 mounted with freedom for rotation upon a shaft 28 journaled at its respective opposite ends in the front- and back-plates 20 and 21.

The driving-wheel 26, above referred to, is provided with a rigid forwardly-projecting anchor-stud 29 around which is hooked one end of a helical transmitting-spring 30 which functions intermittently to transmit the movement of the driving-wheel 26 to an electric switch or other desired device, in a manner as will hereinafter appear.

The transmitting-spring 30 is preferably formed of spring wire and has its major portion housed or shielded within a spring-barrel 31 which latter together with a stop-arm 32 is staked or otherwise rigidly attached to a driven-pinion 33 mounted upon the shaft 28 before referred to, and rigidly coupled thereto. The end of the transmitting-spring 30 opposite the end thereof coupled to the anchor-stud 29 is extended forwardly through an aperture 34 in the spring-barrel 31 and is bent over the forward face of

the stop-arm 32 as shown. As thus constructed and arranged, the transmitting-spring 30 elastically transmits the force developed by the driving gear-wheel 26 to the stop-arm 32 and hence to the driven-pinion 33 by which the said stop-arm is carried.

At its outer end the stop-arm 32 is bent inwardly to provide a radially-extending latching-finger 35 normally in engagement with a latching-finger 36 formed at the outer end of a yielding latching-member 37. The said latching-member 37 may be of any suitable form which will yield to permit the retirement of the latching-finger 36 and, as herein shown, the said latching-member is formed of spring-metal having at its end opposite from the said latching-finger, an anchoring-tongue 37a extended through the back-plate 21 and riveted in place therein.

For the purpose of periodically retiring the latching-finger 36 of the latching-member 37 out of the path of movement of the latching-finger 35 of the stop-arm 32, a latch-releasing member 38 is employed. The said latch-releasing member is mounted for swinging movement about an axis transverse to the plane of movement of the latching-member 37, upon a stud 38a carried by the driving gear-wheel 26. The said latch-releasing member 38 is located to the rear of the driving gear-wheel 26 by which it is carried, and is provided at points remote from the stud 38a about which it swings with a forwardly-projecting latch-releasing pin 39 and a forwardly-projecting actuating-pin 40. Both the latch-releasing pin 39 and the actuating-pin 40 of the latch-releasing member 38 project forwardly through an arcuate clearance-slot 26a formed in the driving gear-wheel 26, as is especially well shown in Fig. 8 of the drawings.

The latch-releasing pin 39 of the latch-releasing member 38 is adapted to engage with the inner face of the latching-member 37 and is sufficiently short to readily pass by the rear edge of the latching-finger 35 of the stop-arm 32. The actuating-pin 40 of the said latch-releasing member 38 is longer than the pin 39 and is adapted to engage with the latching-finger 35 of the stop-arm 32 as the latch-releasing member 38 is carried bodily by the driving gear-wheel 26, to effect the turning movement of the latch-releasing member 38 for the purpose as will more fully hereinafter appear.

The driven-pinion 33 before referred to, meshes into a gear-wheel 41 mounted with freedom for rotation upon a shaft 42 journaled at its respective opposite ends in the back-plate 21 and in a cup-shaped bearing-member 43 secured in and forwardly-projecting from the front-plate 20. The said gear-wheel 41 is provided with two (more or less) spring-paws 44—44 which engage with the teeth of a pinion 45 for driving the latter in the same direction as the gear-wheel 41 is driven, but which permits the said pinion to be advanced as desired relative to the said gear-wheel 41. The pinion 45 extends through the front-plate 20 into the interior of the cup-shaped bearing-member 43 and projects radially through the cut-away side wall 46 of the said bearing-member into engagement with a gear-wheel 47 located forwardly of the front-plate 20. The gear-wheel 47 is rigidly mounted upon a hub 48 turning upon a stud 49 forwardly projecting from the front-plate 20 as is shown in Fig. 2. At its forward end, the hub 48 has rigidly attached to it a control-wheel or member 50

preferably formed in its entirety of insulating material so as to guard against the access of stray electrical currents to the parts above described.

The control-wheel 50, just above referred to, will, in a manner as will hereinafter appear, have imparted to it step-by-step rotational movement in the direction indicated by the arrow in Fig. 1, and as the parts are proportioned in the particular instance shown, each step-by-step movement of the said control-wheel 50 will be substantially 10° or one-thirty-sixth revolution.

The control-wheel 50 is provided upon its periphery with three (more or less) cam-lugs respectively numbered 51, 52 and 53, and spaced from each other by an equal number of clearance-notches respectively numbered 54, 55 and 56. Each of the cam-lugs 51, 52 and 53 is adapted to sequentially coat with an inclined cam-finger 57 formed at the outer or free end of a resilient contact-arm 58. The said contact-arm 58 is secured by means of suitable screws 59—59 to an insulating-block 60. The said insulating-block 60 is secured to the forward face of the front-plate 20 in any suitable manner such, for instance, as by screws 61—61.

About midway of its length, the resilient contact-arm 58 is provided with a movable contact 62 adapted to periodically engage with a similarly-shaped stationary contact 63 carried at the outer end of a relatively-rigid contact-bracket 64 secured to the insulating-block 60 by means of screws 65—65.

Respectively clamped against the outer end of the contact-arm 58 and the outer end of the contact-bracket 64, by means of their respective outer screws 59 and 65, are lead wires 66 and 67 which may be extended to a device which it is desired to electrically control. The device to be controlled may, of course, assume a wide variety of forms and is not per se involved in the present invention, but by way of illustration, such device may be considered to be an automatic washing machine or the like.

In order to make clear the operation of the device illustrated, let it be assumed that the parts are in the positions in which they are illustrated in Figs. 1, 2 and 3, and that a supply of alternating current is connected to the synchronous electric motor-structure 23. Under these conditions, the driving-pinion 25 would effect the continuous rotation of the driving gear-wheel 26 and the parts coupled thereto. As the driving gear-wheel 26 turns, it will add to the tension of the already pre-tensioned transmitting-spring 30 so that the said transmitting-spring with gradually increasing force will tend to turn the stop-arm 32 in a clockwise direction. At this time, however, the said stop-arm 32 is held against turning movement by the engagement of its latching-finger 35 with the latching-finger 36 of the latching-member 37.

Now when, in the continued rotation of the driving gear-wheel 26, the said gear-wheel carries the latch-releasing member 38 to a position so as to engage its actuating-pin 40 with the latching-finger 35, the said latch-releasing member will be turned about the stud 38a in a clockwise direction to cause the latch-releasing pin 39 to press outwardly upon the free end of the latching-member 37 as is shown in Fig. 4 of the drawings.

When the latching-member 37 has been flexed sufficiently to clear its latching-finger 36 from the latching-finger 35 of the stop-arm 32, the

said stop-arm 32 and the parts connected thereto will rapidly swing through an arc of 360° in a clockwise direction under the urge of the transmitting-spring 30. The instant that the stop-arm 32 moves as just described, its latching-finger 35 will move away from the actuating-pin 48 of the latch-releasing member 38 and thus relieve the latching-member 38 of outward thrust, so that the said latching-member may instantaneously swing its latching-finger 35 inwardly into the path of movement of the latching-finger 35 of the stop-arm 32. The latching-finger 35 will thus be in position to be engaged by the latching-finger 35 of the stop-arm 32 when the same has completed one full revolution, whereupon the parts directly involved will assume the positions in which they are illustrated in Fig. 5, preparatory to another cycle of operation. It may be here explained that as the latch-releasing member 38 moves bodily in a clockwise direction with the driving gear-wheel 26 from the position in which it is shown in Fig. 5, the latch-releasing pin 39 of the said member 38, owing to its relative shortness, will ride freely past the rear-edge 25 of the latching-finger 35 of the stop-arm 32 without engaging the same.

It will be understood from the foregoing and by reference to the accompanying drawings, that when the stop-arm 32 is unlatched as above described, to permit the transmitting-spring to assert itself to effect one complete revolution of the said stop-arm and of the driven-pinion 33, the control-wheel 50 will be turned one step which under the conditions shown is sufficient 35 to ride the cam-lug 51 out from under the cam-finger 57 of the contact-arm 58 and to shift the clearance-notch 56 thereunder to thereby permit the contact 26 to engage with the contact 63.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. A rotary motion translating device comprising in combination: a substantially-continuously-rotating driving-member; an intermittently-driven member having a latching-abutment; a transmitting-spring operatively-connected to both the said members and forming a yielding driving-connection therebetween; a retrieable latching-member releasably engageable with the latching-abutment of the said intermittently-driven member to restrain the latter; and a latch-releasing member carried by and bodily movable with the said driving-member and being brought into engagement with a portion 55 of the said intermittently-driven member while the same is restrained by the said latching-member to shift the said second abutment and cause the same to retire the said latching-member.

2. A rotary motion translating device comprising in combination: a substantially-continuously-rotating driving-member; an intermittently-driven member having a latching-abutment; a transmitting-spring operatively connected to both the said members and forming a yielding 75 driving-connection therebetween; a retrieable

latching-member releasably engageable with the latching-abutment of the said intermittently-driven member to restrain the latter; and a latch-releasing member pivoted to the said driving-member for bodily movement therewith and for pivotal movement with respect thereto, the said latch-releasing member having a releasing-abutment and a stop-abutment which latter is engageable with a portion of the said intermittently-driven member while the same is restrained by the said latching-member and while the latch-releasing member is being bodily moved by the said driven-member to cause the latch-releasing member to swing with respect to the said driving-member by which it is carried and thereby force the said releasing-abutment to retire the said latching-abutment and thus release the said intermittently-driven member to the action of the said transmitting-spring.

3. A rotary motion translating device comprising in combination: a substantially-continuously-rotating driving-member; an intermittently-driven member having a latching-abutment; a transmitting-spring operatively connected to both the said members and forming a yielding driving-connection therebetween; a retrieable latching-member releasably engageable with the latching-abutment of the said intermittently-driven member to restrain the latter; and a latch-releasing member carried by the said driving-member and connected thereto with the capacity for movement substantially parallel with the plane of movement thereof, the said latch-releasing member having a first abutment projecting substantially perpendicularly therefrom and a second abutment also projecting substantially perpendicularly therefrom, the said first abutment being engageable with a portion of the said intermittently-driven member while the same is restrained by the said latching-member, to shift the said second abutment and cause the same to retire the said latching-member.

4. A rotary motion translating device comprising in combination: a substantially-continuously-rotating driving-member; an intermittently-driven member having a latching-abutment; a transmitting-spring operatively connected to both the said members and forming a yielding driving-connection therebetween; a retrieable latching-member releasably engageable with the latching-abutment of the said intermittently-driven member to restrain the latter; and a latch-releasing member pivotally carried by and bodily movable with the said driving-member and having swinging movement about an axis substantially parallel with the axis of the said driving-member, the said latch-releasing member having a releasing-abutment and a stop-abutment which latter is engageable with a portion of the said intermittently-driven member while the same is restrained by the said latching-member and while the latch-releasing member is being bodily moved by the said driven-member, to cause the latch-releasing member to swing with respect to the said driving-member by which it is carried and thereby force the said releasing-abutment to retire the said latching-member and thus release the said intermittently-driven member to the action of the said transmitting-spring.

5. A rotary motion translating device comprising in combination: a substantially-continuously-rotating driving-member; an intermittently-driven member having a latching-abutment; a transmitting-spring operatively connected to both the said members and forming a yielding 75

driving-connection therebetween; a latching-member formed of spring-metal and having an offsetting latching-abutment releasably engageable with the latching-abutment of the said intermittently-driven member to restrain the latter; and a latch-releasing member pivotally connected to the said driving-member and bodily movable therewith, the said latch-releasing member having a releasing-abutment and a stop-abutment which latter is engageable with a portion of the said intermittently-driven member while the same is restrained by the said latching-member, to cause the latch-releasing member to swing with respect to the said driving-member and thereby force the said releasing-abutment to flex the said latching-member and disengage its latching-abutment from the latching-abutment of the said intermittently-driven member.

6. A rotary motion translating device comprising in combination: a substantially-rotating driving-gear; timing-means for turning the said driving-gear at a predetermined rate of speed; an intermittently-driven unit comprising a gear and a stop-arm rigidly connected with the said gear and having a latching-abutment; a transmitting-spring operatively connected to both the said driving-gear and the said intermittently-driven unit and forming a yielding driving-connection therebetween; a retrievable latching-member releasably engageable with the latching-abutment of the stop-arm of the said intermittently-driven unit to restrain the same; and a latch-releasing member carried by and bodily movable with the said driving-gear with respect to which latter it has movement, the said latch-releasing member having a first abutment and a second abutment, the said first abutment being brought into engagement with a portion of the stop-arm of the said intermittently-driven unit while the same is being restrained by the said latch-member to shift the said second abutment and cause the same to retire the said latching-member.

7. A rotary motion translating device comprising in combination: a substantially-continuously-rotating driving-gear; timing-means for turning the said driving-gear at a predetermined rate of speed; an intermittently-driven unit comprising a gear and a stop-arm rigidly connected with the said gear and having a latching-abutment; a transmitting-spring operatively connected to both the said driving-gear and the said intermittently-driven unit and forming a yielding driving-connection therebetween; a retrievable latching-member releasably engageable with the latching-abutment of the stop-arm of the said intermittently-driven unit to restrain the same; and a latch-releasing member pivoted to the said driving-gear for bodily movement therewith and for pivotal movement with respect thereto, the said latch-releasing member having a releasing-abutment and a stop-abutment which latter is engageable with a portion of the said intermittently-driven unit while the same is being restrained by the said latching-member and while the said latch-releasing member is being bodily moved by the said driving-gear to cause the latch-releasing member to swing with respect to the said driving-gear by which it is carried and thereby force the said releasing-abutment to retire the said latching-member and thus release the said intermittently-driven unit to the action of the said transmitting-spring.

8. A rotary motion translating device comprising in combination: a substantially-contin-

uously-rotating driving-gear; timing-means for turning the said driving-gear at a predetermined rate of speed; an intermittently-driven unit comprising a gear and a stop-arm rigidly connected with the said gear and having a latching-abutment; a transmitting-spring operatively connected to both the said driving-gear and the said intermittently-driven unit and forming a yielding driving-connection therebetween; a retrievable latching-member releasably engageable with the latching-abutment of the stop-arm of the said intermittently-driven unit to restrain the same; and a latch-releasing member carried by the said driving-gear and connected thereto with capacity for movement in a plane substantially parallel with the plane of movement thereof, the said latch-releasing member having a first abutment projecting substantially perpendicularly therefrom and a second abutment also projecting substantially perpendicularly therefrom, the said first abutment being engageable with a portion of the said intermittently-driven unit while the same is being restrained by the said latching-member, to shift the said second abutment and cause the same to retire the said latching-member.

9. A rotary motion translating device comprising in combination: a substantially-continuously-rotating driving-gear; timing-means for turning the said driving-gear at a predetermined rate of speed; an intermittently-driven unit comprising a gear and a stop-arm rigidly connected with the said gear and having a latching-abutment; a transmitting-spring operatively connected to both the said driving-gear and the said intermittently-driven unit and forming a yielding driving-connection therebetween; a retrievable latching-member releasably engageable with the latching-abutment of the stop-arm of the said intermittently-driven unit to restrain the same; and a latch-releasing member pivotally carried by and bodily movable with the said driving-gear and having swinging movement about an axis substantially parallel with the axis of the said driving-gear, the latch-releasing member being provided with a releasing-abutment and a stop-abutment which latter is engageable with a portion of the said intermittently-driven unit while the same is being restrained by the said latching-member and while the said latch-releasing member is being moved by the said driving-gear, to cause the latch-releasing member to swing with respect to the said driving-member by which it is carried and thereby force the said releasing-abutment to retire the said latching-member and thus release the said intermittently-driven unit to the action of the said transmitting-spring.

10. A rotary motion translating device comprising in combination: a substantially-continuously-rotating driving-gear; timing-means for turning the said driving-gear at a predetermined rate of speed; an intermittently-driven unit comprising a gear and a stop-arm rigidly connected with the said gear and having an offsetting latching-abutment; a transmitting-spring operatively connected to both the said driving-gear and the said intermittently-driven unit and forming a yielding driving-connection therebetween; a latching-member having one portion fixed to the structure of the device and formed of spring-metal and having an offsetting latching-abutment releasably engageable with the offsetting latching-abutment of the stop-arm of the said intermittently-driven unit to restrain the

the same; and a latch-releasing member pivotally connected to the said driving-gear and bodily movable therewith, the said latch-releasing member having a releasing-abutment and a stop-abutment which latter is engageable with a portion of the said intermittently-driven unit while the same is being restrained by the said latching-member to cause the said latch-releasing member to swing with respect to the said driving-gear and thereby force the said releasing-abutment to flex the said latching-member and disengage its latching-abutment from the latching-abutment of the stop-arm of the said intermittently-driven unit. 5

ARTHUR B. POOLE.
